UNITED STATES PATENT OFFICE.

HARRIS H. HAYDEN, OF NEW YORK, N. Y.

STORE-SERVICE APPARATUS.

SPECIFICATION forming part of Letters Patent No. 295,248, dated March 18, 1884.

Application filed December 27, 1883. (No model.)

To all whom it may concern:

Be it known that I, HARRIS H. HAYDEN, of the city, county, and State of New York, have invented certain new and useful Improvements 5 in Store-Service Apparatus, of which the following is a specification.

My invention relates to that class of store-service apparatus in which balls or spherical carriers travel upon ways between the main 10 desk and stations at the counters, and where each station may be provided with two or more carriers of the same size; and my invention is designed to provide means for receiving any one of the carriers, or all at once, and 15 for delivering them to the clerk one by one without confusion or risk of accident.

While my invention is available with different kinds of systems employing different forms of carriers, I have illustrated it in connection with a system employing tracks consisting of parallel inclined rails, and carriers 20 consisting of hollow balls containing the cash and memoranda.

In the drawings, Figure 1 is a side elevation 25 of part of the return-way at one of the stations, showing my invention. Fig. 2 is a part plan of Fig. 1. Fig. 3 is a sectional elevation of Fig. 2. Fig. 4 is a side elevation, showing a modification. Fig. 5 is a sectional elevation 30 of Fig. 4. Fig. 6 is a perspective view, showing the track and drop-switch-operating mechanism.

A is the delivery-track, carrying the balls from the main desk to the counters, and provided at intervals with drop-switches B and with locking devices C, and appliances graduated in respect to the graduated balls, so that each ball will unlock the switch at the station where it should be delivered. The locking 35 device C consists of a horizontal lever, a, pivoted to one of the rails of the track and catching under a lip, b, of the drop-switch, so as to hold in line with the track a post, c, supporting a lever, d, carrying an arm, f, and 40 connecting with the lever a, so that when the arm f is struck by a ball the lever a will be carried from the drop-switch and will release the latter, permitting it to tilt, as in Fig. 1, and deliver that ball to the receiving-track below, being the same device described in W. S. Lamson's Patent No. 258,585. Each arm f is adjustable, so that it may be set to be struck

only by the balls that are to be delivered at that point.

The receiving-track consists of a secondary 55 track, A', suspended below the track A, and, as shown, consisting of light wires j, connected at one end by a cross-piece or wire, h, turned up to serve as a stop and prevent the carriers rolling back and escaping from the 60 track, and with guard-wires i, that prevent the carriers from escaping laterally. The wires are spread or opened at the lower end, or other means provided, so that a ball may pass freely downward into a basket or receptacle, D, suspended below the opening. The basket is suspended in any suitable manner, so that it is retained in place until a ball or carrier passes into the same, and may then descend, either under the weight of the carrier or by 70 being drawn down by means of a cord, k. A cord passing over pulleys and having a counter-weight at the end may be used; but I prefer to employ one or more drums, E, each containing a coiled spring, (shown in dotted lines, Fig. 75 1,) which will turn the drum to wind up the suspension-cords L to lift the basket, but will yield to permit the latter to be drawn down. When spring-drums are used, I place one at 80 each side of the way, as shown in Fig. 2; but one drum may be employed and be arranged horizontally beneath the main track, the two cords l extending over guide-pulley m to the drum, as shown in Figs. 4 and 5.

As one or more carriers will sometimes pass 85 to the track A' while one is in the basket, it is necessary to prevent those on the track from dropping through the opening when the basket is drawn down. This I effect by means of a stop device of any suitable character so arranged as to hold the carriers on the track A' when the basket is down. Thus in Figs. 1, 2, and 3 the stop device consists of a pendent swinging yoke, F, and notched lever G, in the notch at the end of which the cross-piece of the yoke 90 catches, being thereby held so as to prevent the balls from passing beyond the position shown in Fig. 3. An arm, m, extends from the shaft supporting the lever G to a position to be struck by the basket when it is at its 95 upper position, to thereby lift the catch-lever G, release the yoke-detent, that it may swing to the position shown in Fig. 1, and permit the ball to pass into the basket. So long as

the ball is in the basket it holds the yoke in the position shown in Fig. 1; but as soon as the basket is drawn down the yoke swings to the position shown in Fig. 3, and prevents the 5 passage of another carrier until the basket is again in place beneath the opening. A different form of detent is shown in Figs. 4 and 15, where the yoke is normally horizontal, the 10 balls striking its cross-piece, and a pendent arm, *n*, is struck by the basket when the latter rises to lift the yoke to the position shown in Fig. 5, out of the way of the carrier entering the basket. To the basket is pivoted a lever, *H*, which, when the basket is at its upper 15 position, falls to a horizontal position, the ball then passing over it and into the basket, thereby turning the lever to a vertical position, (dotted lines, Fig. 5,) so that its upper end will prevent the next ball from passing inward 20 while the yoke *F* is lifted.

By providing a receptacle for the balls beneath the track, and by combining with this a delivery device whereby the carriers may be taken separately from the receptacle, I am 25 enabled to take the carriers from the main track without obstructing the latter, to take and hold several carriers in succession belonging to one station, and to deliver each carrier separately into a movable receptacle below 30 the receiving-track, thus greatly facilitating the working of a line in a busy store, and thereby avoiding extended structures at the sides of the track, the whole apparatus occupying no more room than the width of the 35 track.

By making the receiving-track of wire I avoid the weight resulting from the use of other materials, avoid noise, and the apparatus is less prominent to the eye, and therefore 40 less objectionable than if more bulky materials were employed.

The spring-drums are effective in elevating the basket, but are small, light, and do not add materially to the bulk of the structure.

45 It will be apparent that where different forms of ways and carriers are employed the receiving-way and movable receptacle and detents will be varied accordingly.

It will be apparent that the above-described 50 device may be employed when the carriers are switched onto a supplemental receiving-way on a level with the main way.

Without limiting myself to the precise construction of parts shown, I claim—

55 1. The combination, with the main way and switch of a store-service apparatus, of a sup-

plemental receiving-way and a movable receptacle arranged below the receiving-way to receive the carriers passing from the latter, substantially as set forth. 60

2. The combination of the main way and switch and a receiving-way having an opening whereby the carriers may descend vertically, a vertically-moving receptacle below the receiving-way, and a detent whereby the carriers are retained on the receiving-way until the receptacle is at its highest point, substantially as described. 65

3. The combination of the main track and switch, receiving-way having the tracks 70 spread at the delivery end, detent, and receptacle or basket arranged below the opening in the track, and connected to cords and counterbalanced, substantially as specified.

4. The combination, with the main way and 75 switch of a store-service apparatus, of a receiving-way arranged below the main way, and a movable receptacle arranged below the receiving-way to receive the carriers passing vertically from the latter, substantially as set 80 forth.

5. The combination of the main track and switch, receiving-way, basket, suspension-cords, and one or more spring-drums, upon 85 which said cords are wound, substantially as described.

6. The combination of the main track, switch, and receiving-way, consisting of wires arranged below the main way and provided with a detent, substantially as described. 90

7. The combination of the receiving-way, receptacle, detent, and locking device, whereby the detent is locked in place until the receptacle is at its highest point, substantially as 95 described.

8. In a store-service system, a return-way provided with a series of switches and appliances whereby each switch is unlocked at its proper station, and a receiving-way adjacent to each switch, and a movable receptacle and 100 appliances whereby the carriers on the receiving-ways may be successively carried downward to the operator's station, substantially as specified.

In testimony whereof I have signed my name 105 to this specification in the presence of two subscribing witnesses.

HARRIS H. HAYDEN.
